UNITED STATES PATENT OFFICE.

LEWICKI J. LEON, OF WEST CHICAGO, ILLINOIS.

LATCH.

Original application filed January 10, 1925. Serial No. 1,576. Divided and this application filed October 5, 1925. Serial No. 60,465.

This invention relates to a latch construction and consists in the matters hereinafter described and claimed and is a division of my copending application Serial No. 1,576, filed January 10, 1925, for "bird cages."

In the accompanying drawings—

Fig. 1 is a view of a bird-cage equipped with a latch means of my invention;

Fig. 2 is a top plan view of the bottom wall of the cage;

Fig. 3 is an enlarged vertical sectional view on line 3—3 of Fig. 1;

Fig. 4 is a vertical sectional view on line 4—4 of Fig. 1;

Fig. 5 is a top plan view of the latch structure on line 5—5 of Fig. 3;

Fig. 6 is a side view of the operating member of the latch;

Fig. 7 is a top plan view of the same; and

Figs. 8 and 9 are top plan views of the washer and latch member, respectively.

In Fig. 1, I have shown a bird-cage having a cage body 1 and a base 2. The latter has an upright marginal wall 3 and a detachable bottom wall 4. The cage body 1 is secured to the base 2 by a ring 5 at the lower end of the body fitting in a channel 6 around the upper edge of the base 2, as shown in Fig. 4. The outer marginal portion 7 of the bottom wall 4 is offset considerably below its center portion and extends outward under and provides a seat for the lower edge of the base 2, as shown in Fig. 3.

Latch means of my invention is applied to said bottom wall 4 in spaced relation about the periphery of the same for releasably holding the bottom wall in the base.

Each latch means comprises a latch member 8 on the inside of the bottom wall 4 and an actuating member 9 on the outside of said wall, as shown in Fig. 3. These members 8 and 9 are connected together for turning through the interposed portion 10 of the wall 4, so that on turning the outer member 9 the inner or latch member 8 is swung into or out of a channel 11 in the marginal wall 3. The latch member or plate 8 is preferably flat and has a straight front edge, as shown in Figs. 2 and 5, to engage against the wall 3 in the channel 11 for holding the latch member from accidental turning when engaged with said wall 3.

When applied to a bird-cage, the outer members 9 are below the bottom wall 4, and, in addition to being actuating members,

serve as feet for the cage, as shown in Fig. 1.

The members 8 and 9 of each latch means are connected together as follows. The member 9 is formed to have a flat body portion 12 at its inner end, and this body portion fits up against the under side of the adjacent wall portion 10 about a hole 13 therein. Said body part 12 has an upstanding annular flange 14, which extends upwardly through said hole 13 and forms a bearing 65 for the member 9 against the edge of said hole as the member is turned.

The height of the flange 14 is greater than the gauge or thickness of the wall portion 10, and said flange has two upstanding, oppositely disposed tongues 15, 15, which extend upward through slots 16, 16 in the latch member or plate 8 to connect the latter to the member 9. The upper ends of these tongues are upset or riveted over the 75 member 8, as shown in Fig. 3. A washer 17 is interposed between the member 8 and the wall portion 10 to space the member 8 above the same and prevent scratching of said wall portion as the member 8 is turned.

The construction shown and described eliminates the necessity of a separate rivet and avoids drawing the parts 8 and 9 into cone shapes against the wall as in the case when a separate rivet is used. This is due to the fact that the upper edge of the flange 14 provides a relatively wide and continuous bearing surface for the member 8, thereby supporting it against inward bending when riveted to the flange by the tongues 15. 90 Moreover, this flange 14 supports the plate 8 above and out of contact with the wall, so that the parts are free to turn without binding in actuating the latch through the member or handle 9. The flange 14 also provides 95 a relatively wide lateral bearing surface for the edge of the opening in the wall and avoids cutting into the metal of the wall in the repeated turning of the latch parts, and provides a firm and permanent setting so that the parts will not readily work themselves out of place. The opening made in the wall to accommodate the flange 14 is covered by the plate 8, as shown in Fig. 5,

thus making a neat finish and adapting the 105 latch construction for use on ornamental articles. Furthermore, the latch structure and the wall to which it is applied may be made from relatively light sheet material and be sufficiently strong and rigid to ac- 110

complish results which otherwise would require much heavier material.

While I have shown and described my improved latch means as applied to bird-cages, it may be used for other devices. Moreover, the details of structure shown and described may be variously changed and modified without departing from the spirit and scope of my invention.

10 I claim as my invention:

1. The combination with a wall, of latch means carried thereby and comprising a latch member on one side of the wall and an actuating member on the other side of said wall, one of said members being provided with an annular flange extending through a hole in the wall and engaging the edge of the same throughout the thickness of the wall, the other member being connected with the

20 first member through and supported by said flange so that the latch member may be turned by the actuating member.

2. The combination with a wall, of latch means, comprising a latch member on one side of the wall and an actuating member on the other side of said wall, one of said members having an annular flange extending through a hole in the wall with the flange engaging the edge of the hole throughout the

30 width of the wall, said flange having tongues

projecting beyond the wall and extending through slots in the other member to connect the members together so that the latch member may be turned by the actuating member.

3. The combination with a wall, of latch means carried thereby and comprising a latch member on one side of the wall and an actuating member on the other side of said wall, one of said members being provided with an annular flange extending through a hole in the wall and engaging the edge of the same throughout the thickness of the wall, the other member being connected with the first member through said flange so that the latch member may be turned by the actuating member, and a washer between the latch member and wall for holding the latch member out of contact with said wall.

4. The combination with separable walls, of latch means carried by one of said walls and having latch and actuating members on opposite sides of said wall and connected together for turning through said wall, said latch member having a straight end edge to engage the other wall for holding said latch member against accidental turning.

In testimony whereof I affix my signature this 1st day of October, 1925.

LEWICKI J. LEON.
